LEON BEAUMON, OF HOLLYWOOD, LOS ANGELES, CALIFORNIA.

DIRECTION SIGNAL.

Application filed March 4, 1927. Serial No. 172,709.

This invention relates to and has for a main object the provision of a new and novel direction signalling device for use on motor vehicles, whereby a right or left hand turn, or a stop may be indicated to on-coming traffic prior to a change in direction being made.

Another object is to provide a signal in the form of an arm, or semaphore attachable to the vehicle adjacent the driver's seat and provided with one or more Neon or other gas tubes adapted to be energized for indicating different signals.

A particular object of this invention is to provide a signalling arm adapted to be pivotally supported at one end and having an elongated aperture longitudinally disposed in the arm, and a gas filled tube disposed in the aperture and supported on the arm, and visible from both sides of the arm, the cross section of the arm being greater than that of the tube so that the tube will be protected against damage.

A further object is to provide manual means for operating the arm and automatic means for energizing the lamps, selectively, corresponding to the signal desired to be made.

Other objects may appear as the description progresses.

I have shown a practical embodiment of my invention in the accompanying drawing, subject to modification within the scope of the appended claims without departing from the spirit thereof.

In said drawings:

Fig. 1 is a perspective view of my signal applied to a closed motor car, in readiness for use;

Fig. 2 is a perspective view of the manually operable means for connection and operating the signal;

Fig. 3 is a perspective view of the signal arm, or semaphore, embodied in the signal apparatus;

Fig. 4 is a circuit diagram showing the electrical connections;

Fig. 5 is a perspective view of the contact plunger for regulating the illumination of the lamps.

Briefly described, the device consists of a

signal arm S having lamps L and L' mounted thereon, and an operating mechanism including a handle H, lever h, shaft G and sector J, as shown in Fig. 2 adapted for connection with the arm S for operating said arm, as shown in Fig. 1.

Signal S has a metallic head A in the form of an arrow, and a tail fixture F which are spaced apart substantially and are connected by means of a pair of parallel metallic tubes T and T'. Members A and F are perforated on adjacent sides to receive the opposed ends of a pair of glass Neon lamp tubs L and L' which illuminate the signal. Lamp L has electrodes E and E' and lamp L' has similar electrodes e and e', respectively, at the opposite ends thereof, for connection with the wires of an electric system, for energizing the lamps.

The inner ends of lamps L and L' are imbedded in a suitable block of insulating material I, such as vulcanite or the like, within the fixture F while the electrodes E and e' project therefrom into the switch chamber 1 of said fixture. A contact plunger P is slidably mounted in the fixture F at right angles to the lamps L and L', as shown, and carries a pair of spaced contacts C and C', arranged, respectively, for contact with the electrodes E and e of lamps L and L'.

Plunger P is insulated from and mounted in a pair of thimbles D and D' mounted in the fixture F, and has a head d of insulating material projecting from one side of the fixture F. The other end of the plunger is provided with a reduced stem d' within the thimble D' and carries a coiled spring 2 which normally urges the plunger upwardly to and maintains the same in normal position, so that the contacts C and C' will disengage the electrodes E and e of lamps L and L'.

The stem d' of the plunger P is connected with a wire W which leads to a terminal of a distributor switch M, and the electrodes E' and e' of lamps L and L' are commonly connected at 3 with wire W', which is grounded at 9. Terminal 4 of the distributor M is connected by means of a wire 5 with a high tension coil 6' which is grounded at 8' and is inductively connected with a low tension coil 6.

Said coil 6 is connected with a battery 7 which is grounded at 8 and the circuit is completed through interrupter 4' to ground 7'.

A metal plate B is provided for covering 5 one side of the fixture F and the same is attached thereto by means of screws 10, 10, etc. Said fixture has a bore 11 therethrough which receives a hinge pin, or screw 12 attachable to the corner post 13 of the car body, or to 10 another convenient part of the body, whereby the arm S may swing downwardly from a normally upright position to various positions indicated by broken lines in Fig. 1, for indicating different signals.

15 Centrally of the car I provide the operating means shown in Fig. 2. Said means includes a handle H fixed to the inner end of a horizontal shaft G, mounted in the front panel, or frame, 14 of the windshield, and 20 movable over a sector J provided with notches for holding the handle in different positions. The outer end of shaft G carries an arm h adapted for connection with the arm S by means of a wire rod R, as shown, 25 the outer end of said rod being pivoted to a fitting r attached to one edge of the fixture F.

By reference to Fig. 3 it will be observed 30 that the rod R is in the plane of and engages the upper side of the head d of the plunger P, and as the arm S is swung downwardly said rod depresses the plunger correspondingly, and serves to move the contacts C and C' into engagement with the electrodes E 35 and e of lamps L and L'. When, however, the arm S is at rest in an upright position the plunger will be so positioned as to hold the contacts out of engagement with the electrodes so that the lamps L and L' will be normally deenergized.

As shown in the drawings, Fig. 1, in full 40 lines, the arm S indicates a right hand turn and the lamp L' will be energized and should preferably show a green, or safety light. 45 This is occasioned by the contact of member C' with electrode e in the movement of the arm S to first position. The other two positions of the arm are for left hand turn and stop, progressively, and the movement of the 50 arm to such positions disengages the contact C' from electrode e of lamp L' and engages contact C with electrode E of lamp L, causing lamp L to glow red—the danger signal.

If desired or necessary a shield or suitable 55 enclosure 18 may be attached to the car body for protecting the arm S when the same is inoperative, and other means may be employed than that shown for operating the arm S.

What I claim is:

60 1. A direction signal for motor vehicles comprising a rigid arm, and a Neon light tube mounted longitudinally in said arm for producing a colored direction signal, said tube being supported inwardly of the sides thereof 65 for protecting the tube against damage, and

visible when illuminated, from opposite sides of the arm.

2. A direction signal for motor vehicles comprising a signal arm having an elongated central aperture therein open at opposite 70 sides of the arm, and a gas filled tube disposed in said aperture for producing the color of the signal, said arm projecting laterally from the periphery of said tube for protecting the tube against breakage. 75

3. A direction signal comprising a signal arm adapted to be pivotally supported on a vehicle and having an elongated central aperture therein open at opposite sides of the arm, and a Neon gas filled tube disposed 80 in said aperture and supported at its ends on said arm.

4. A direction signal comprising an arm in the form of an arrow and provided with an elongated central aperture therein open at 85 opposite sides of the arm, a gas filled tube disposed in said aperture and visible through the aperture from both sides of the arm, the cross sectional area of said arm being greater than the area of said tube, for protecting 90 the tube against damage.
